UNITED STATES PATENT OFFICE.

HARRY HARDWICK, OF PHILADELPHIA, PENNSYLVANIA.

WOVEN PILE FABRIC.

SPECIFICATION forming part of Letters Patent No. 518,883, dated April 24, 1894.

Application filed May 9, 1892. Serial No. 432,285. (No model.)

To all whom it may concern:

Be it known that I, HARRY HARDWICK, a citizen of the United States, and a resident of Philadelphia, Pennsylvania, have invented 5 certain improvements in Woven Pile Fabrics, of which the following is a specification.

The object of my invention is to provide for using as warp threads in the manufacture of woven fabrics, yarns such as have not hitherto been available for such use, and this object I attain by combining a coarse yarn of such hitherto unavailable material with a finer yarn or strand which has the effect not only of materially increasing the tensile 15 strength of the doubled yarn, as compared with that of the single coarse yarn, but also prevents the cutting or excessive chafing of said coarse yarn by the heddles or reed in the operation of weaving. The yarns which 20 I contemplate using are those made of mohair, short staple wool stock, cotton, hair, or the like.

My invention is applicable to the weaving of fabrics generally, but is especially intended 25 for use in the weaving of cut pile fabrics in which the surface is formed by the upturned ends of the fibers of the yarn, the presence of the fine strands being less noticeable in this class of fabrics than in those in which the 30 fabric is woven with a flat warp or with an uncut pile.

In the accompanying drawings:—Figure 1, is an exaggerated view of a piece of my improved yarn; and Fig. 2, is an exaggerated 35 longitudinal section of a piece of cut pile fabric in the manufacture of which such improved yarn has been employed.

Ordinarily, in fabrics such as damask, Brussels, Wilton, or velvet carpets, a good quality 40 of wool must be employed in the yarns for the warps so that said yarns will be strong enough to resist the tensile strain upon the warps and the scraping or rubbing to which said warps are subjected in their passage 45 through the eyes of the heddles and dents of the reed and by reason of the contact of the warps with each other during the shedding operation. In carrying out my invention, however, I propose, in one case, to use for the 50 warp, a yarn made from a low grade of wool or from mixtures of wool and hair or other

adulterant, such as are now commonly employed as weft or filling threads in the manufacture of ingrain carpets. Owing to the inferior character of the material, these yarns 55 cannot be drawn to produce fine strands, hence such yarns are coarse, and generally have a comparatively loose twist so that they are not adapted for use as warp threads, for the reasons above set forth. I find, however, 60 that by combining the coarse yarn of such inferior wool or mixed fiber with a finer strand or yarn, the doubled yarn, without any material increase either of bulk, weight or cost, is rendered sufficiently strong to effectually 65 resist the tensile strain to which it is subjected when used as a warp thread, and furthermore, that the fibers of the coarse yarn are held so closely together that the yarn will not be scraped or abraded to the breaking point in 70 its passage through the heddles and reed or by the successive sheddings of the warp.

In Fig. 1 of the drawings A represents a 75 yarn of inferior wool or mixture such as I have described, and B the fine yarn doubled therewith, the amount of twist imparted to the doubled yarn being varied as circumstances may suggest, although in practice I have found that a very light twist, say one turn in three-quarters of an inch or an inch, 80 is sufficient for the purpose. The fine yarn has more twist than the coarse yarn, and the operation of doubling is preferably such as to increase the twist of the coarse yarn to the extent of the doubling twist. 85

Both the coarse and the fine yarn may consist of either one or more strands, and the coarse yarn may be of any material which, of itself, is incapable of use as a warp thread in the manner in which the doubled yarn is to 90 be used. If the coarse yarn is composed of cotton, the fine yarn may be of the same material, but if said coarse yarn is of inferior wool, or other inferior stock, or of mohair or other stock which, in the form of yarn, has 95 but little tensile strength, the fine yarn should be of different material, as for instance of cotton, linen, or even worsted if desired, although cotton is preferred as the cheapest, and has been found to be effective in practice. 100

The coarse and fine yarns are substantially of the same length so that the strain is exerted

upon them equally and simultaneously; and also when the pile is cut after the yarns are woven into a pile fabric thus setting the threads free to untwist, they will remain the same length whereby an even cut pile surface is produced.

The pile fabric shown in Fig. 2 has the usual backing fabric of interwoven warps *a* and wefts *b* and pile warps *d* interwoven 10 with and retained by the wefts *b* of said backing fabric, said pile warps consisting of the doubled and twisted yarns.

Having thus described my invention, I claim and desire to secure by Letters Patent—

1. The within described warp thread consisting of a twisted coarse yarn of material incapable of use alone as a warp thread, and a finer twisted yarn wound upon the surface 20 thereof, the twist being in the same direction in both yarns and the said yarns being sub-

stantially of the same length whereby they may bear equal strain, substantially as and for the purpose set forth.

2. The within described cut pile fabric consisting of a backing of interwoven warps and wefts, and pile-forming warps combined with said backing fabric, and consisting of twisted coarse yarns of material incapable of use alone as warp threads, and finer twisted yarns wound upon the surface thereof, twisted in the same direction therewith, the said yarns being substantially of the same length whereby they may bear equal strain, substantially as and for the purpose set forth.

In testimony whereof I have signed my name to this specification in the presence of two subscribing witnesses.

HARRY HARDWICK.
